[57] CLAIM

The ornamental design for a beverage dispenser, as shown and described.

DESCRIPTION

FIG. 1 is a front perspective view of a beverage dispenser showing the right side of my new design; FIG. 2 is a rear perspective view of the left side thereof; FIG. 3 is a top plan view thereof on a reduced scale; FIG. 4 is a front elevational view of a modified form of the beverage dispenser showing my new design. The sides, top and rear view of this modified form are substantially identical to those shown in FIGS. 1, 2, 3 and 6;

FIG. 5 is a front elevational view of the beverage dispenser shown in FIGS. 1-3; and

FIG. 6 is a right side elevational view of the beverage dispenser shown in FIG. 1. The left side of the beverage dispenser being substantially identical to the right side.

FIG. 1

FIG. 3

FIG. 2

FIG. 4

FIG. 5

FIG. 6
